United States Patent Office

Des. 197,915
Patented Apr. 7, 1964

197,915

UTILITY TOOL

Nancy F. Ayars, 4404 La Crosse Ave., San Diego, Calif.

Filed Oct. 22, 1962, Ser. No. 72,213

Term of patent 14 years

(Cl. D54—13)

FIG. 2

FIG. 1

FIG. 3

FIG. 1 is a side view of the utility tool showing my new design;

FIG. 2 is an end view of the utility tool; and

FIG. 3 is a fragmentary sectional view along the line 3—3 of FIG. 1.

The side opposite that shown in FIG. 1 is substantially plain.

I claim:

The ornamental design for a utility tool, as shown and described.
